Primary Examiner — Philip S Hyder(74) *Attorney, Agent, or Firm* — Boyle Fredrickson S.C.(57) **CLAIM**

The ornamental design for a deep cleaning alignment tool, as shown and described.

DESCRIPTION

FIG. 1 is a perspective view of a deep cleaning alignment tool, showing our new design;

FIG. 2 is a top plan view thereof;

FIG. 3 is a side elevation view thereof;

FIG. 4 is a front elevation view thereof; and,

FIG. 5 is a rear elevation view thereof.

The uneven broken lines define the boundaries of the claim. The even broken line illustrate portions of the deep cleaning alignment tool in which the design is embodied the form no part of the claimed design.
